CLAIM

The ornamental design for a rock singer-shaped pasta, as shown and described.

DESCRIPTION

FIG. 1 is a front elevational view of rock singer-shaped pasta showing our new design, the undisclosed rear being a mirror image;

FIG. 2 is a left side elevational view thereof;

FIG. 3 is a right side elevational view thereof;

FIG. 4 is a top plan view thereof; and,

FIG. 5 is a bottom plan view thereof.

FIG. 4

FIG. 2

FIG. 1

FIG. 3

FIG. 5
